ARTIST'S KIT

Alan Geller, 233 E. 32nd St., New York, N.Y.
Filed July 9, 1963, Ser. No. 293,765
7 Claims. (Cl. 297—135)

This invention relates in general to an artist's paint kit, and more specifically to an artist's paint ensemble complete with easel, stool, palette and means for containing and carrying paints, brushes and other painting accessories necessary for painting, which can be readily set up for use or compactly stowed for ease of carrying or storing the same.

Heretofore, artists' paint kits generally consisted of a carrying case made of either wood or metal which was constructed and arranged so as to be capable of carrying or storing merely the artist's paints, brushes, and other tools of his art. Whenever an artist was required to paint a canvas, as for example, out-of-doors and away from his studio, it was necessary for him to transport in addition to his paint case, an easel and more than likely a stool in order to complete his ensemble of working equipment. Because easels are cumbersome and bulky in nature, the artist generally had difficulty in transporting or moving all of his equipment from site to site.

Therefore it is an object of this invention to provide an artist's kit complete with easel, stool, palette and means for containing and carrying paints, brushes, and other painting accessories and the like, which can be compactly stowed, stored or carried in a novel wrapper-type carrier which is relatively light in weight, easy to carry and relatively inexpensive to make.

It is another object of this invention to provide a novel artist's kit complete with easel, stool, palette and means for containing and carrying paints and brushes wherein structure of the easel is such that it defines a rigid frame structure for the kit.

It is another object of this invention to provide an artist's ensemble complete with easel having telescopically adjustable legs which can be readily extended between retracted and protracted positions, and which can be readily knocked down between operative and inoperative positions.

It is another object of this invention to provide an artist's kit complete with stool which can be readily set up between stowed inoperative position and unstowed operative position simply and quickly without the use of any tools, and which in the stowed position complements the easel so as to define a rigid frame structure for the kit in the stowed position thereof.

It is another object of this invention to provide a novel wrap-around construction formed of foldable material constructed and arranged so as to be readily foldable about the easel and stool in the knockdown position thereof, to define the carrying case whereby the assembled kit can be readily carried with a maximum of ease and occupying a minimum of space.

It is another object to provide an artist's ensemble with a novel palette arrangement constructed and arranged so as to be carried in a pocket formed in the wrapper carrier, and which is constructed and arranged so as to facilitate the folding of the wrapper about the collapsed easel structure in the stowed position of the ensemble and thereby forming a rigid side structure for a portion of the kit.

It is another object to provide an artist's kit in which, in the set-up position thereof, the wrapper forming the carrier may be suspended from the easel in a manner so that the paints and accessories carried thereby are rendered readily accessible to the artist working upon the canvas positioned on the easel.

2

It is still another object to provide an easel construction which can be readily assembled and disassembled with a maximum of ease and without the use of any tools, and in its knockdown position defines a rigid frame structure for the kit.

5 Another object of this invention is to provide an easel and stool combination constructed and arranged so that in the respective knockdown position thereof, one can be readily nested within the other so as to define a compact frame structure about which a foldable wrapper is folded to define a compact kit.

10 Another object is to provide a novel wrapper-type carrier provided with pockets to receive tubes of paint, brushes, and other artist accessories and in which the pockets are located so that they fall between the rigid 15 members of the frame about which the wrapper is folded.

Another object of the present invention is to provide a 20 novel artist's kit ensemble including a flaccid wrapper type carrier provided with pockets formed on one surface thereof, the pockets being adapted to receive and hold tubes of paint, brushes, and other artist's accessories, the flaccid wrapper type carrier being adapted to be wrapped around a rigid frame formed by the legs of an easel, the pockets lying on the interior of the 25 wrapper in its wrapped around condition and being protected by the rigid frame formed by the legs of the easel.

The foregoing objects, features, and other advantages are attained by an artist's ensemble comprising a sheet 30 of foldable material which is adapted to be wrapped about a rigid frame construction which is defined by the easel and a stool in the respective knockdown positions thereof. In accordance with this invention the inner side of the sheet is provided with means for defining a plurality of pockets for holding the respective tubes of paint, 35 brushes or other painting accessories. Accordingly, the ensemble of this invention is complete with collapsible easel and stool used in conjunction therewith.

The easel comprises a tripod base construction having 40 telescoping legs which are adapted to be extended between protracted operative position and retracted inoperative position with means for securing the legs in their adjusted extended positions. Means are also provided for bracing the legs in the operative position thereof.

45 In accordance with this invention means are provided on the sheet whereby the sheet can be suspended from the brace which maintains the tripod base of the easel in erected position so that the paints may be positioned and held in place before the artist, and thereby be rendered readily accessible to him as he is working on the canvas supported thereon.

A collapsible stool is also included on which the artist may be seated and it comprises a frame to which 55 three legs are pivotally connected for movement between operative and inoperative position. A readily removable seat is secured to the upper ends of the respective legs to form the body support. Accordingly, the easel and stool may be each knocked down so that the respective leg portions thereof are disposed parallel and substantially coincident to one another in which the respective legs are triangularly disposed. The arrangement is such that the diameter of the stool legs is greater than that of the tripod legs so that one may be nested in the other in the collapsed position thereof. Thus in the collapsed 60 position of respective easel and stool, these nested within 65 one another form a rigid frame structure. To stow the kit, the collapsed and nested easel and stool are disposed upon a portion of the expanded wrapper and the wrapper in turn folded about the legs of the easel and stool to enwrap the same to define a carrier whereby the easel and stool may be readily transported, the arrangement 70

being such that the respective pockets receiving the paints are disposed within the side spaces between the nested leg structures of the easel and stool. A suitable fastening means is provided for securing the ends of the wrapper about the frame defined by the easel and nested stool. A means forming a pocket on the exterior or outer side of the wrapper is also provided, and it receives the palette. The palette of this invention comprises a plurality of hinged sections to facilitate the folding of the wrapper about the frame structure in the stowed position of the kit. A means defining a handle is also provided for facilitating the portage of the stowed kit.

A feature of this invention resides in the provision of a novel artist's kit complete with collapsible easel, collapsible stool and the necessary artist's accessories which are adapted to be compactly stowed in the inoperative position thereof so as to form a kit which is light in weight, readily portable, and easy to operate.

It is another feature of this invention to provide an artist's kit in which the structure of the easel and stool utilized in the respective knockdown position thereof defines a rigid frame structure about which a wrapper is folded, the rigid structure protecting the artist's paint supplies and accessories positioned within the folds of the wrapper.

Another feature of this invention resides in a novel easel construction which can be readily assembled and disassembled without the use of any tools, and which easel is sturdy in construction and simple in operation.

Another feature resides in a unique stool which is adapted to be folded between operative and inoperative position, and which in the inoperative position thereof can be stowed in conjunction with the collapsed easel to define a rigid frame for the artist's kit.

Another feature of this invention resides in the utilization of the palette as means for reinforcing the side portions of the artist's kit of this invention.

Other features and advantages will become more readily apparent when considered in view of the drawings and description applied thereto in which:

FIG. 1 is a perspective view of the artist's kit in accordance with this invention;

FIG. 2 illustrates a plan view of the artist's kit in its opened position;

FIG. 3 is a cross-sectional view taken along line 3—3 of FIG. 1;

FIG. 4 is a cross-sectional view taken along line 4—4 of FIG. 2;

FIG. 5 is a detailed view illustrating the various component parts which make up the easel construction, and in which the tripod portion of the easel is illustrated in its collapsed, inoperative, stowed position;

FIG. 6 illustrates an elevation view of the easel tripod base construction in its assembled or set-up position;

FIG. 7 is a plan sectional view taken along line 7—7 of FIG. 6;

FIG. 8 is a perspective view of the artist's stool which forms a component element of the artist's kit of this invention; and

FIG. 9 is a detailed perspective view of the foldable palette utilized in conjunction with the artist's kit of this invention.

Referring to the drawings, there is shown in FIG. 1 the assembled view of the artist's kit or ensemble 10 which constitutes the instant invention. In accordance with this invention, the artist's kit 10 of FIG. 1 is complete with easel 11, stool 12 on which the artist may be seated while working upon the easel, and all the necessary paints 13, brushes 14 and other artist's accessories neatly stowed and compartmentized within the kit 10. In the operative position, the respective component parts of the kit can be readily set up so that every part of it is rendered useful.

In the illustrated embodiment the kit 10 comprises an outer wrapper 15, which can be formed of any flaccid or

foldable sheet of material, i.e., any suitable fabric or foldable plastic material. For example, the wrapper 15 defining the kit 10 may be formed of a rectangular sheet of canvas material. As shown, the wrapper 15 has on its inner surface means for defining a series of pockets 16 adapted to receive and hold the painting accessories, as for example, the respective tubes 13 of varied colored paints, brushes and the like. While the means defining the respective pockets 16 for containing the tubes of paint 13 may be positioned along the inner side of the wrapper in any desired manner, in the illustrated embodiment a sheet of material, as for example, clear plastic to permit viewing of contents of pockets, is secured to the wrapper sheet 15 to provide a series of loops 16 as best seen in FIG. 3 to define the pockets 16. Pockets 16 may be open or closed on the ends. The arrangement of the pockets or loops 16 on the inner side of the wrapper is such that they will fall between the adjacent corners of the rigid frame structure defining the kit 10 as will be hereinafter described in greater detail.

In the illustrated arrangement one series of pockets 16A is located adjacent one end of the sheet and another series of pockets 16B at the other end with a series 16C disposed at an intermediate portion of the sheet. Extending longitudinally of the sheet and adapted to be located between the bottom members of the rigid frame structure is another pocket 17 for containing other artist's supplies, as for example, brushes 14 and the like. If desired, a flap 17A, adapted to be fastened to the pocket, may be provided so as to prevent the accessories therein from becoming loose therefrom. Suitable fastening means 18 may be provided to secure the flap 17A to the pocket 17.

As best seen in FIG. 2, a slide fastener 19 is secured along the longitudinal edge portion of the wrapper 15. Intermediate the width thereof and adjacent the other longitudinal edge portion of the wrapper 15 is a complementary slide fastener 20. The arrangement is such that in the folded position of the wrapper 15, the respective slide fasteners 19, 20 have complementary engaging portions to secure the wrapper 15 in the assembled position thereof, as in FIG. 1.

In accordance with this invention the kit or ensemble 10 is complete with easel and stool. The easel and stool are specifically constructed and arranged so that in the knockdown positions thereof, they combine to define a rigid frame structure 21 for the artist's kit. As shown in FIGS. 2, 3, and 5 to 7, the easel 11 construction comprises a top plate 22 to which are connected brackets 23 which have pivotally connected thereto legs 24, 25, 26 defining a tripod base for the easel. As viewed in FIG. 3, the top plate 22 of the tripod base is hexagonal in plane view and forked brackets 23 are secured thereto. Pinned to each of the brackets 23 is a leg member of the easel. In the illustrated embodiment the respective leg members of the easel comprise telescoping leg sections which are adapted to extend between retracted inoperative position as viewed in FIGS. 2 and 5, and protracted extended position as viewed in FIG. 6. Means in the form of screw clamp 27 is secured to each of the outermost leg members so that the corresponding inner leg member may be retained in its extended position.

Slidably connected to two of the legs 24, 26 is a holding means 28 which may be adjustably positioned along the length of the outermost section of their respective leg members for receiving a brace means 29 by which the respective legs may be rigidly positioned in the assembled position of the tripod base. As best seen in FIG. 5 the brace means 29 comprises a T-shaped element in which the stem 29A of the T element is hingedly connected to the crosspiece 29B of the element at a point intermediate the ends thereof so as to define a three-armed brace. A series of spaced notches 29C are formed along the ends of the crosspiece 29B. Thus as seen in FIGS. 6 and 7, in order to brace the respective legs 24, 25, 26 of the

tripod base in operative position thereof, the holding means 28 are slidably adjusted therealong to a suitable position for accommodating the T-shaped brace.

As seen in FIG. 7, the holding members 28 on two of the legs comprise a U-shaped slide 28A which has threaded in the web or base end thereof a set screw 28B for positioning the slide at a given position along the length of the leg members. An angled pin 28C is inserted through openings formed in the legs of the U-shaped slide 28B for embracing the legs of the tripod. According to the invention the pin 28C extends beyond the slide 28B and it is provided with an angle offset at the end thereof.

The other leg 25 of the tripod is provided with an adjustable strap clamp or collar 30 which is tightened about the leg to fix the position thereof by a screw 31 having a flat head 31A. Accordingly the strap clamp or collar 30 may be slidably adjusted by simply turning the screw 31.

As shown in FIGS. 5 and 7, the stem 29A of the brace adjacent the free end thereof is provided with a horizontally slotted hole 32 which is adapted to receive the flat head 31A of the screw when the flat head is horizontally disposed. Thus to brace the legs 24, 25, 26 of the tripod in an operative position thereof, the respective holders or slides 28 and the collar strap 30 are adjustably positioned to a common level. The brace 29 is then positioned between the legs 24, 25, 26 of the tripod so that the cross-piece 29B is seated on the pins 28C of the slide 28 fixed to legs 24 and 26 by resting one of the notches 29C on the respective ends thereof. The stem 29A of the brace 29 is aligned so that the head 31A of the strap clamp screw 31 is received in the slotted opening 32. By turning the flat head 31A vertically or 90 degrees the stem 29A of the brace 29 is fixed to the strap collar. Thus the three points of the brace 29 are fixed relative to the respective legs of the tripod base. With the brace 29 so fixed in position, it will be noted that the respective leg members of the tripod are firmly secured and fixed with respect to one another to provide a stable support for the canvas 33 supported by the easel.

In accordance with this invention, as seen in FIGS. 6 and 7, with the tripod erected in its operative position as described, the sheet 15 containing the respective artist's colors and brushes may be suspended therefrom by threading the crosspiece 29B of the T-shaped brace member 29 through the loops 34 connected along the edge portion of the wrapper 15. Thus, as is shown in FIG. 6, the wrapper 15 may be dependently suspended from the cross-arm 29B of the brace to thereby render the colors stored within the respective pockets 16 thereof readily accessible to the artist as he works upon a canvas supported on the tripod.

To support the canvas 33 upon the tripod base of the easel, a clamping means 35 is provided. As shown in FIG. 5 the clamping means 35 for supporting the canvas 33 upon the easel comprises a bar member 36 which has formed therein a series of holes 36A longitudinally spaced along the length thereof. Pivotally connected to one end of the bar 36 is a C-shaped clamp 37 and the C-clamp is secured to the bar by a suitable screw and wing nut fastener. Connected intermediate the ends of the bar 36 is a second bar 38 and it is secured thereto by a suitable fastener, e.g., a suitable screw and wing nut. A C-shaped clamp 39 is connected to the free end of the second bar 38. Thus the bracket 35 is constructed so that it is secured to the top of the tripod with one of the clamps and the other is positioned to engage the top of a canvas 33. The bottom of the canvas is supported on the extended portion of the angle pins 28C of each of slide members 28, as seen in FIG. 6. In this manner by a simple bracket 35 or adaptor utilized in conjunction with the slides 28 there is provided a stable three point support for a canvas 33.

If desired, non-skid tips 40 may be provided to the

end of the innermost leg members of the tripod telescoping leg members.

The kit 10 in accordance with this invention also includes a stool 12. In accordance with this invention the stool 12 comprises a substantially triangular brace or frame means 41, the corners or apexes thereof being squared or flat. Accordingly the leg members 42 of the stool 12 are pivotally connected to the frame 41 by means of a pin or pivot 43 about which the respective legs 42 can rotate.

In the illustrated embodiment the respective leg members 42 of the stool 12 are defined by hollow tubular members which have an internal diameter substantially greater than that of the outermost leg member defining the legs of the tripod base. It will be readily noted that the legs 42 of the stool 12 can be rotated between operative and inoperative position with respect to its frame member so that in the inoperative stowed position the respective legs of the stool are disposed in substantially parallel relationship with the legs being disposed in a triangularly spaced relationship with respect to one another, and that in the assembled erected position of the stool the respective leg members 42 are rotated approximately 45 degrees counter-clockwise with respect to their respective points of pivots 43 so as to define a rigid tri-legged stool.

Detachably connected to the upper ends of the respective stool leg members 42 is a seat 44 formed of a fabric material or the like. The seat has provided at the corners thereof a pocket 44A for receiving the upper ends of the respective leg members 42. Thus in the operative position of the stool, the seat portion receiving the upper end of the stool legs limits the rotation of the respective legs about their pivots. As seen in FIG. 8, the stool 12 in the assembled position forms a rigid support capable of sustaining a considerable load. With the easel 11 erected, the stool 12 may be utilized in conjunction therewith so as to provide an artist maximum comfort during a painting session.

In accordance with this invention the entire kit or ensemble 10 including easel, stool, paints, brushes, accessories and the like can be readily set up or stowed in a minimum of lost time or effort.

As shown in FIGS. 2, 3 and 4, the stool 12 in the collapsed position thereof defines a structure in which its respective legs 42 are disposed parallel to one another, and spaced one from another in a triangular relationship. The easel 11 construction, when disassembled, also has its legs 24, 25, 26 pivoted to a position where they extend parallel to one another and likewise disposed in substantially triangular configuration. Thus both the stool and easel, in the disassembled position thereof, have their respective legs angularly disposed so that the legs of the easel can be received or telescopically nested within the tubular portions of the stool legs 42, as is clearly evident in FIGS. 2 and 3. As noted in FIG. 2, the top plate 22 of the easel 11 defines one end of a rigid frame structure 21 and the triangular frame 41 of the stool 12 defines the other rigid end structure of the frame 21, with the respective leg members of the easel and stool defining the rigid longitudinal members therebetween. In their knockdown position, the nested easel 11 and stool 12 are positioned on the expanded wrapper 15, as indicated in FIG. 2 so that the pocket 17 containing the brushes is disposed between two of the base legs which define the bottom portion of the rigid frame structure 21 formed by the easel and the stool. The T-shaped brace 29 of the easel 11 and the bracket 35 are folded and disposed between the leg members which define the rigid frame structure 21 and between the top plate 22 and stool frame 41. Therefore with the nested easel 11 and stool 12 disposed in the manner described on the expanded wrapper 15, it will be noted that the wrapper 15 need only be folded about the rigid frame 21, defined, so that the entire kit 10 can be confined within the perimeter of the

wrapper 15, as is evident in FIG. 1. With the sheet 15 folded about the rigid frame structure, the slide fasteners 19, 20 are secured to hold the wrapper about the frame. If desired the end portions of the wrapper 15 may be tucked flush against the respective ends of the kit and secured in place by end straps 46 which are provided for this purpose.

If desired a palette 48 may be also included as part of the initial kit. In accordance with this invention as shown in FIG. 9, the palette 48 comprises a substantially rectangular flat member formed of hinged sections. As shown a relatively narrow section 48A has hinged to each longitudinal edge thereof an outer end section 48B, 48C. In accordance with this invention the foldable wrapper 15 is provided on the external surface thereof with a flap 49 to define an open end pocket, as is shown in FIG. 3. With the sheet in its expanded position the palette 48 may be disposed within the pocket 50 and arranged so that the hinged sections 48B, 48C thereof fold with the portions of the wrapper which define two sides 20 of the kit in a manner illustrated in FIG. 3. Thus, the respective hinged sections 48A, 48B, 48C of the palette form a rigid side portion for the kit in the stowed position.

To facilitate portage of the kit described, handle means 25 51 may be provided. As shown in FIG. 1 the handle means 51 comprises a carrying strap which has a handle grip 52. Connected to each end thereof is a loop 53 through which a wrapping strap 54 is threaded. One end of each wrapping strap 54 is provided with a buckle 30 55 through which the other end of the wrapping strap may be threaded and secured. From the foregoing disclosure, it will be noted that the artist's kit 10 complete with easel 11, stool 12, palette 48 and the necessary accessory equipment can be readily set up or stowed in 35 a neat, compact arrangement which occupies a minimum of space, and which when stowed provides an arrangement which can be easily carried. The specific component parts of the easel and of the stool may be made of lightweight tubular aluminum or the like. Thus 40 the completed carrying kit is light in weight and easily carried with one hand. An artist can move all necessary equipment from scene to scene with maximum ease and with minimum effort. The respective components of the artist's kit can be readily set up without any tools, and can be readily set up and put away with a minimum of 45 effort and in a minimum of time. It is to be further noted that the outer foldable wrapper 15 not only serves as a means for containing all the necessary artist's accessory equipment, but it also serves as a means for maintaining the artist's colors in position so as to be readily 50 accessible to him during a painting session.

While the instant invention has been illustrated and described with reference to a particular embodiment thereof, it will be readily understood and appreciated that various modifications and variations thereof may be made without departing from the spirit or scope of the invention.

What is claimed is:

1. An artist's paint kit comprising: 60
  - (a) a flaccid wrapper,
  - (b) an easel having collapsible legs which are adapted to extend between operative protracted position and inoperative retracted position,
  - (c) an artist's stool having pivotally connected legs for movement between operative and inoperative positions,
  - (d) said stool legs being formed of hollow tubular construction,
  - (e) the legs of said easel in the collapsed position thereof being adapted to be received in the tubular legs of said stool, and
  - (f) said stool and easel defining a rigid frame structure of said kit when placed on said wrapper and 75

said wrapper folded about said stool and easel so nested to form a carrier therefor, (g) and means for securing said wrapper in its folded position.

2. An artist's paint kit comprising:
  - (a) a wrapper of foldable material,
  - (b) means forming pockets on said wrapper,
  - (c) an easel having collapsible legs which are adapted to extend between operative protracted position and inoperative retracted position,
  - (d) an artist's stool having pivotally connected legs for movement between operative and inoperative positions,
  - (e) means defining a seat detachably connected to said stool legs,
  - (f) said stool legs being formed of hollow tubular construction,
  - (g) the legs of said easel in the collapsed position thereof being adapted to be nested in the tubular legs of said stool, and
  - (h) said stool and easel defining a rigid frame structure when placed on said wrapper so that said wrapper may be folded about said nested stool and easel to form a carrier therefor,
  - (i) and means for securing said wrapper in its folded position.
3. The invention as defined in claim 2, wherein
  - (a) said securing means including a slide fastener.
4. An artist's kit comprising:
  - (a) a foldable carrier formed of a single sheet of material,
  - (b) means defining a series of pockets formed on the inner side of said sheet, said pockets being adapted to hold tubes of paint and brushes,
  - (c) means formed on the outer side of said sheet for defining an outside pocket,
  - (d) means defining a rigid frame for said foldable carrier,
  - (e) said frame means including an easel having a top member, and leg member pivotally connected thereto to define an easel base,
  - (f) said easel base legs including telescoping members which are adapted to extend between operative protracted position and inoperative retracted position,
  - (g) means for positively retaining said legs in protracted position,
  - (h) brace means for maintaining the position of said legs fixed in the operative position,
  - (i) and a bracket detachably connected to said top for holding thereon a canvas,
  - (j) a stool for use with said easel,
  - (k) said stool including a frame structure,
  - (l) tubular stool leg members swivelly connected to said frame structure whereby said stool legs may be rotated between operative and inoperative stool forming position,
  - (m) said easel in the collapsed position thereof having its legs nested in telescoping fashion within the tubular legs of said stool to reduce the overall length of said kit, whereby said easel and nested stool define a triangular frame which is adapted to be positioned on said carrier in the stowed position thereof, and the ends of said carrier being foldable about said frame,
  - (n) and a palette carried in said outside pocket.
5. The invention as defined in claim 4 wherein
  - (a) said palette including hinged sections for facilitating the folding of said carrier about said frame whereby said palette forms means for rendering the sides of said carrier rigid,
  - (b) and detachable handle means wrapped about said carrier for facilitating the carrying of the same.
6. An artist's ensemble adapted to be compactly stowed and rendered readily portable comprising:
  - (a) a foldable carrier formed of a single sheet material,

- (b) means defining a series of pockets formed on the inner side of said sheet, said pockets being adapted to hold tubes of paint and brushes,
  - (c) means formed on the outer side of said sheet for defining an outside pocket,
  - (d) means defining a rigid frame for said foldable carrier,
  - (e) said means including a collapsible easel having a top member and leg member pivotally connected thereto to define a tripod easel,
  - (f) said legs including telescoping sections which are adapted to extend between operative protracted position and inoperative retracted position,
  - (g) means for retaining said legs in protracted position,
  - (h) brace means for maintaining the position of said legs fixed in the operative positions thereof,
  - (i) holding means for detachably securing said brace means to said legs,
  - (j) said holding means including holder slidably disposed along the respective legs,
  - (k) and a bracket detachably connected to said top, said bracket being rendered adjustable for holding thereon a given size canvas,
  - (l) a stool for use with said easel,
  - (m) said stool including a frame structure,
  - (n) tubular stool leg members swivelly connected to said frame structure whereby said legs may be rotated between operative and inoperative stool forming position,
  - (o) a flexible seat detachably disposed on the upper ends of said legs,
  - (p) said easel in the collapsed position thereof having its legs nested in telescoping fashion within the tubular legs of said stool to reduce the overall length of said kit, whereby said easel and nested stool define a triangular rigid frame which is adapted to be positioned on said wrapper in the stowed position thereof, and the ends of said wrapper foldable about said frame,
  - (q) means for securing the wrapper in its folded position,
  - (r) and a palette carried in said outside pocket,
  - (s) said palette including hinged sections for facilitating the folding of said wrapper about said frame whereby said palette forms means for rendering the sides of said wrapper rigid,
  - (t) and detachable handle means wrapped about said wrapper for facilitating the carrying of the same.
7. An artist's kit including a complete ensemble of easel, stool, paint holder and palette, which is adapted to be readily set up for use and compactly stowed away for ease of carrying or storage comprising:
- (a) a foldable carrier formed of a single sheet of substantially rectangular fabric,
  - (b) a slide fastener connected along the longitudinal edge of said sheet, and
  - (c) a complementary slide fastener extending adjacent the other longitudinal edge of said sheet,
  - (d) a series of loops connected to said other end of said sheet,
  - (e) means defining a series of pockets formed on

- one side of said sheet, said pockets being adapted to hold tubes of paint and brushes,
- (f) means formed on the other side of said sheet for defining a pocket adapted to receive the palette,
- (g) means defining a rigid frame for said foldable carrier,
- (h) said means including an easel having a substantially triangularly shaped top member, and a plurality of leg members pivotally connected thereto to define a tripod easel base,
- (i) said tripod legs including telescoping members adapted to extend between operative protracted position and inoperative retracted position,
- (j) means for retaining said legs in protracted position,
- (k) a brace for maintaining the position of said tripod legs fixed in the operative position thereof,
- (l) means for detachably securing said brace to said legs,
- (m) said connecting means including holders slidably disposed along the respective legs,
- (n) and a bracket detachably connected to said top, said bracket being rendered adjustable for holding a given size canvas,
- (o) a stool for use with said easel,
- (p) said stool including a substantially triangular frame structure,
- (q) a plurality of tubular stool leg members swivelly connected to said frame structure whereby said legs may be rotated between operative stool forming position and inoperative knockdown position,
- (r) a flexible seat detachably disposed on the upper ends of said stool legs,
- (s) said easel in the collapsed position having its legs nested in telescoping fashion within the tubular legs of said stool legs to reduce the overall length of said kit, said easel and nested stool defining a triangularly shaped frame which is adapted to be positioned on said carrier in the stowed position thereof so that the ends of said carrier are foldable about said frame and fastened by said slide fastener,
- (t) and a palette carried in said palette pocket,
- (u) said palette including hinged sections for facilitating the folding of said carrier about said frame whereby said palette forms means for rendering the sides of said carrier rigid,
- (v) and detachable handle means wrapped about said carrier for facilitating the carrying of the same.
